IRONING BOARD

George Browning, Wilmette, Ill.

Application March 1, 1939, Serial No. 259,081

2 Claims. (Cl. 38—104)

This invention relates to ironing boards of the type adapted for use with a hand iron as is common for ironing cloths and other articles in the home. The general practice heretofore has been to employ a rigid board on which is placed a pad of fibrous material and on top of that an ironing cloth on which the article is ironed, or to employ an ironing cover of fabric material of appreciable thickness.

As the iron is manipulated during the ironing operation, the moisture in the dampened article being ironed is converted into vapor or steam, some of it escaping into the atmosphere and some entering the cold pad where it condenses, with the result that the pad or covering over part of the board becomes moisture laden to a greater or lesser degree depending on the kind of work being ironed and the initial moisture content thereof. As a consequence, the time and physical effort required for ironing depends to a considerable degree on the elimination of this moisture in order to complete the ironing operation with the article in a smooth and dry condition.

One of the objects of my invention is to provide an improved ironing board designed to enable ironing in less time and with less physical effort than heretofore.

My invention contemplates broadly as one of its objects the provision of means for heating the ironing board substantially uniformly throughout its working area, whereby to aid in evaporating the moisture at all portions of the working surface and to render more effective the localized ironing action of the heated iron.

Another object of my invention is to provide an improved ironing board heated electrically, and to this end I have disclosed herein several embodiments which promote greater efficiency in time and effort for ironing.

Among the further objects of my invention are to provide an electrically heated ironing board characterized by a thin sheet of aluminum or other material of high heat conductivity serving as a supporting base for the pad or ironing cover, together with an electric element arranged to heat said aluminum sheet in such manner as to effect substantially uniform distribution of heat to the said ironing pad or cover throughout its working area; to provide an ironing pad or cover combined with an electrically heated supporting base of thin sheet metal having high heat conductivity to effectively serve the purposes desired; to provide for

the application of such an ironing board structure either as an attachment to an ordinary ironing board or as a complete assembly having its own means of support such as the usual folding legs; to provide a heated ironing board having a relatively thin sheet metal base heated for the purpose described and reinforced on its under side by ribs or the like to provide a flat and rigid work supporting surface, this embodiment being preferable as a complete structure as distinguished from an embodiment for the application to an ordinary ironing board; and to provide an improved ironing board structure which may be economically produced and which will serve in a satisfactory manner the purposes intended.

Other objects and attendant advantages will be appreciated by those skilled in this art as the invention becomes better understood by reference to the following description when considered in connection with the accompanying drawings, in which:

Fig. 1 is a top view of an ironing board embodying my invention;

Fig. 2 is an enlarged cross section through the ironing board taken substantially on the section line 2—2 of Fig. 1;

Fig. 3 is a fragmentary plan section taken substantially on the section line 3—3 of Fig. 2;

Fig. 4 is a side elevation of the embodiment shown in preceding figures, with the supporting legs attached;

Figs. 5 and 6 are top and bottom views of a modified form of my invention;

Fig. 7 is an enlarged sectional view taken substantially on the section line 7—7 of Fig. 6; and

Fig. 8 is a cross sectional view of a further modification.

In the embodiment shown in Figures 1 to 4, inclusive, I have shown an electrically heated ironing board applied to the supporting or base board 11 of an ordinary ironing board. The board 11 in turn is supported by the usual folding legs 12, or any suitable means. This board 11 has the shape characteristics common to the ordinary ironing board in general use in homes, consisting of a main body portion of greater length than width, tapering at one end, the major, working portion of the board being of substantial width to accommodate the ironing of larger pieces and the tapered end being adapted for ironing special pieces, as is well understood in the art.

My invention contemplates the provision of a heated ironing board or pad structure adapted

to be supported directly upon a board such as 11, or to be otherwise supported, as described hereinafter. My improved board structure preferably conforms to the general shape of the board 11, as shown in Figure 1. In this connection it will be noted that while ironing boards in general use vary to some extent in respect to length, width, and taper, it is my purpose to provide an improved board structure of such shape and dimensions as to be most universally applicable and to provide special sizes wherever necessary.

In the preferred embodiment herein illustrated, I have provided a sheet 13 of thin aluminum, or other metal of high heat conductivity, which serves as a base or support for an ironing cover. In this instance the ironing cover comprises a pad 14 of fibrous material or the like, and a fabric ironing cloth 15, the parts 13 and 14 being of the size and shape above described for covering the top of the board 11 and the fabric sheet 15 being of such size as to permit of its marginal portions 16 being drawn down around the sides of the board 11 and inwardly over the bottom so that they may be drawn taut and held in this condition. In this instance, a cord 17 is used to lace or draw together the marginal edges of the sheet 15 to retain this sheet as well as the pad 14 and the heated sheet 13 in working position on the board 11. The sheet 13 is heated electrically by means arranged to apply the heat substantially throughout the working area of the ironing board, and in such manner as to obtain substantially uniform distribution of heat throughout such area.

In this instance, resistance wire 18 is arranged in a circuitous path on a sheet 19 of asbestos or other insulation material and is secured thereon at the turns by wire staples 21. Sheets 22 and 23 of similar insulation are applied to the top and bottom, respectively, of the sheet 19, thus serving to insulate the heating element from the aluminum sheet 13. This aluminum sheet constitutes a protective sheath or part of such a sheath, as the case may be, for the insulated heating element.

In this particular embodiment, a second aluminum sheet 24 is applied to the bottom of the insulated heating element, and the marginal edges 25 of the top sheet 13 are turned downwardly under the bottom sheet 24 and clamped thereto so as to bind together the aluminum and asbestos sheets in the manner shown. The insulated heating element is thus encased in an aluminum sheath. The terminal ends 26 and 27 of the heating element lead into an insulation block 28 and connect to the current supply wires 31. The block 28 is preferably of rubber molded to T-shape so as to fill the space between the top and bottom aluminum sheets, as shown in Fig. 2, and provide strain-relief lugs 29 seating against the narrow upright wall portion of the sheet 13. The molded block is also shaped to provide a casing 32 for the lead wires, which casing extends substantially from the heating unit and provides an effective anti-kink device.

Before starting to iron, electric current is caused to pass through the element to heat the pad 14 and the cover 15 through the intermediary of the thin heat distribution sheet 13. Current of comparatively low wattage is continuously supplied throughout the ironing operation, although the current supply may be varied in any suitable manner to maintain the pad and the cover heated throughout the ironing operation. Thus, when a dampened piece to be ironed is

spread on the ironing board and the heated iron is worked back and forth, the moisture content of the piece will be expelled and evaporated by the joint action of the heated iron and the heated board. It will be observed that as a result of the higher temperature of the iron and its action on the dampened piece being ironed, moisture will be expelled therefrom into the padded portion of the board and will be subject to the heat thereof and quickly converted into vapor, thus avoiding the collection of moisture in the ironing pad or cover common to the prior practice. Also, by reason of the heated board or cover, the localized heat of the iron is more effectively utilized in the smoothing function because less heat is lost in dispelling moisture. This is particularly advantageous, because the ironing board is substantially uniformly heated throughout its working area, and the iron with its localized application of heat is instantly effective to a high degree in the performance of its smoothing and drying functions as it is worked back and forth.

As a result of my invention, the time required for ironing a given job is appreciably reduced, and at the same time less physical effort is required. The thin aluminum sheet functions to provide quick distribution of heat by reason of its high thermal conductivity and promotes uniform heat transfer tending to keep the entire pad or working cover at substantially uniform temperature. Also, it provides protection against damage and mechanical abuse, and it further provides protection against electrical shock and prevents pins and other sharp objects from penetrating to the element. It will be further manifest that my invention provides an ironing surface or body which takes care of irregularities in the work piece, such for example as seams and buttons, that it serves to quickly expel any moisture driven into the surface as a result of the ironing operation, and that it also provides for quick and substantially uniform distribution of heat to the working area.

In Figs. 5, 6, and 7 I have shown a modified form of my invention, in which the underside of the heating unit is supported and reinforced by a series of ribs or panels. In the particular embodiment shown, these ribs are in the form of angle iron or channel bars 33, suitably arranged on the underside of the heating unit to give rigid support to the latter and prevent sagging and deflection thereof at intermediate points, and to reinforce and strengthen the structure. The panels 33, or the equivalent, may be fastened to the underside of the heating unit by any suitable means, such, for example, as bolts 34 and rivets 35, the bolts passing entirely through the heating unit and the rivets being fastened only to the lowermost sheet. The heating unit here shown is similar to that above described, comprising top and bottom aluminum sheets 13 and 24 and insulation sheets 19, 22, and 23, together with a heating element 18, except that in the present embodiment the marginal portions of the top sheet 13 are extended to provide a marginal apron 36 extending beneath the channels 33, as shown in Fig. 7. The apron 36 is intended to serve as a support for the heated ironing board where the latter is placed on a table top or the like, and it may also serve to confine the heated ironing board in position on a board 11 of the general type above described, the latter instance being illustrated in Fig. 7. Here, the board 11 is of less width than the heated ironing board. The ironing cover may be of any suitable or preferred

construction, and I have here shown a fibrous pad 14 and a fabric ironing cover 15 similar to the corresponding parts above described. In this embodiment as well as in that first described, the ironing cover is removable from its position on the heating unit for the purpose of repair and replacement, and it also serves to hold the heated ironing board structure in position on the ordinary board 11 when so applied. This is attained by making the marginal portions 16 of 10 sufficient length and drawing them taut under the board by suitable means, such as a cord 17. In this form the heating unit which provides the flat supporting surface for the pad or ironing cover may be of comparatively thin section, and this thin section is reinforced and supported in such manner as to maintain its top surface flat and free from deflection regardless of whether or not the unit is supported on a board such as 11, and regardless of irregularities in the surface 15 of any such supporting means. In this form the channeled structure also provides a heat insulation space at the underside of the heating unit.

In the embodiment Fig. 5, I have shown an 25 electrical connection or terminal box designated generally by 37, having current supply wires 38 leading to the heating element through the intermediary of a suitable switch, the lever of which is shown at 39, and having a socket connection for a terminal plug 41 to which the sad-iron is attached. The switch is arranged for cutting off the ironing board heating element from the sad-iron connection, at will.

The embodiment shown in Fig. 8 is similar to that in Fig. 7 except that the depending side walls or aprons 36 of the heating unit are reinforced by channel irons 42 for the attachment of supporting legs 43. In this form the heating unit which constitutes the ironing board top is reinforced marginally by channel irons 42, or the equivalent, and interiorly by channel irons 33, or the equivalent, and the entire structure is carried on suitable legs which may be of the folding type commonly used with ironing boards. The ironing pad or cover has been omitted from this view, and it will be understood that a pad or cover structure is to be applied in any suitable manner to complete the ironing board.

It will be manifest from the foregoing that my 50 invention provides an improved ironing board characterized by a thin metallic sheet of high

thermal conductivity suitably heated and serving to support the ironing cover and to heat the same preferably throughout its working area as a means of enabling ironing in less time and with less physical effort than with prior constructions. It will also be apparent that my invention in the embodiment herein shown for purpose of illustration is characterized by a heat distribution sheet, such as described, constituting part of an electrical heating unit, and that in this embodiment the heat distribution sheet serves as a sheath to protect the element against damage and mechanical abuse, and also as a protection against electrical shock which might otherwise be occasioned by the penetration of pins and other sharp objects. My invention may therefore be embodied in various forms, and changes may be made in the construction and arrangement of parts in the spirit and scope of the appended claims, in which:

I claim:

1. An electric ironing board comprising, in combination, a flat top ironing board, an ironing cover, a combined ironing base and self-contained heating unit replaceably supported directly on the top of said board substantially coextensive therewith and serving to directly support the ironing cover and to provide the ironing base therefor, said unit comprising a sheath having a 35 top sheet of metal of high heat conductivity and sheets of electrical insulation material superimposed one upon another making a comparatively thin structure, and an electrical heating element in said sheath comprising resistance wire electrically insulated from the sheath by said insulation material and arranged in a circuitous path throughout substantially the entire area of said ironing base whereby to quickly transmit heat substantially uniformly throughout said 40 area, said unit as such being replaceable on said board and adapted to conform to the top thereof by means of the flexible characteristic of the thin sheet structure of the unit and at the same time providing a smooth impervious ironing base for the ironing cover.

2. An electric ironing board as set forth in claim 1, in which the resistance wire is stapled to a sheet of insulation material and the wire as well as the staples are insulated by a sheet of 45 said insulation material placed on the top and another on the bottom of the wire carrying sheet.

GEORGE BROWNING.
